UNITED STATES PATENT OFFICE.

ANSON B. WETHERELL, OF PITTSBURGH, PENNSYLVANIA.

STRUCTURAL SYSTEM.

1,212,720.

Specification of Letters Patent. Patented Jan. 16, 1917.

Application filed March 14, 1913. Serial No. 754,285.

To all whom it may concern:

Be it known that I, ANSON B. WETHERELL, a citizen of the United States, residing at Pittsburgh, in the county of Allegheny and State of Pennsylvania, have invented certain new and useful Improvements in Structural Systems, of which the following is a specification.

This invention relates to metal structural work for buildings, bridges, steel cars and other structural work, and it has for its primary objects the provision of a system whereby the construction may be secured together and fastened in a simple and inexpensive manner, obviating the use of rivets and the other means of fastening at present current in structural work; and the provision of an improved joint for structural work which has the operative and functional characteristics specified. My invention further contemplates an improved joint which has great rigidity and strength and which is simple and does away with the use of rivets; and also the provision of improved means for locking the parts together. These together with such other objects as may hereinafter appear, I attain by means of a construction, various embodiments of which are illustrated in the accompanying drawings, wherein—

Figure 1 is a side elevation of a portion of the structural work for a building showing the application of my invention thereto; Fig. 2 is an end view of Fig. 1; Fig. 3 is an enlarged cross section through my improved joint; Fig. 4 is a section on the line IV—IV of Fig. 2; and Fig. 5 is a perspective illustration of a detail of the invention.

Broadly stated, my invention is intended to reduce the cost of metal structural work for buildings, bridges, steel cars, and the like, by the elimination of the use of rivets, and I accomplish this by providing a rivetless joint structure which is readily put together and when assembled, is rigid and strong and easily locked. To form a joint of this character I provide the parts going to make up the joint with inter-fitting portions preferably fluted or corrugated which are held in position with respect to each other by removable keys.

Referring now to Figs. 1 and 5 inclusive, it will be seen I have shown uprights 7 of the structural work of a building, a rider 8, and stringer-locking members 9, the latter two being supported from the uprights.

The uprights 7 may be of the usual channel formation but I have shown my improved joint structure specifically applied thereto in order to illustrate the various forms to which my invention may be adapted. As shown, the upright comprises two interlocking T-sections 12 which are duplicates of one another. The webs 13 are provided with corrugations 14 and a flange of each T-section is provided with a longitudinally extending groove 15 into which the end of the web of the complementary section fits. The T's are positioned and locked together by sliding them past each other, as will be readily apparent on inspection of Fig. 4. The other flange of each section is provided with a similar groove 16, and the sections are locked in assembled position by means of the key-plates 17, each of which engages the grooves 15 and 16 and abuts the web of a section. This construction prevents separation of the T-sections laterally and at the same time affords ease in assemblage. The members 8 and 9 support the upright against lateral displacement, while they are at the same time so arranged as to be locked in position. The base or flanged portion of the T-sections is provided with a pair of vertical slots 19' adjacent the ends of the section, one on each side of the web. The stringers 9 are adapted to fit into these slots, the inner ends, 19, being corrugated and extending within the upright. The riders 8 are provided with an end plate 20 (see Fig. 4) which is corrugated to correspond with the ends 19. The rider is placed in position by sliding it between the ends of the stringers and a key-plate so that the corrugated portions of the rider and the stringers interlock. By this construction both the riders and the stringers are locked together and to the upright. The weight of the riders is transmitted to the uprights through the stringers. If desired, the stringers may be supported on the U-clips 21 which are hung from the base of a T-section adjacent a slot 19'. As an additional means of supporting the riders, plates 22 provided with bent-over portions 23 against which the riders abut may be provided in the uprights. The key-plates 17 extend above the top of the upright to make a joint with the superimposed upright.

From the foregoing it will be clear that I have provided a joint construction whereby metal structural work may be simply, rig-

idly and securely fastened together without using rivets which form a large proportion of the cost of structural systems at present in vogue. At the same time the entire structure is supported, braced, and locked together vertically and laterally. It is obvious that a considerable variety of changes in detail may be made in the construction herein described without departing from the spirit of my invention and the invention is therefore not limited to the specific construction illustrated.

Having thus described my invention and illustrated its use, what I claim as new and desire to secure by Letters Patent is the following:

1. In metal structural work, the combination of an upright flanged beam, a laterally extending member carried by a flange of the beam having corrugations adjacent the end supported on the flange, and a laterally extending rider having a corrugated end por-

tion adapted to fit the corrugations on the said member and inserted between the beam and the corrugated end of said member.

2. In metal structural work, the combination of an upright flanged beam, a pair of laterally extending members supported on the flanges of the beam with their ends lying adjacent the beam and provided with corrugations, and a rider provided with a corrugated portion adapted to lie between the beam and the corrugated ends of said members and engage the corrugations thereof, and means for supporting the rider against relative downward vertical displacement.

In testimony whereof I have hereunto signed my name in the presence of the two subscribed witnesses.

ANSON B. WETHERELL.
